CLAIM

We claim the ornamental design for an indicia scanner, as shown and described.

DESCRIPTION

FIG. 1 is a first perspective view of an indicia scanner showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is second perspective view thereof;

FIG. 9 is a third perspective view thereof; and,

FIG. 10 is a fourth perspective view thereof.

The broken lines are directed to features of the indicia scanner that form no part of the claimed design. Singular broken lines and unshaded portions contained within broken lines are not claimed.
